(57) **CLAIM**

The ornamental design for electronic vaping device with response draw lighting, as shown and described.

DESCRIPTION

FIG. 1 is a top plan view of a first embodiment of electronic vaping device with response draw lighting, including a triangle-patterned, translucent, illuminable portion, depicted in an unilluminated state.

FIG. 2 is a top plan view of the first embodiment of electronic vaping device with response draw lighting, depicted in a first state of illumination.

FIG. 3 is a top plan view of the first embodiment of electronic vaping device with response draw lighting, depicted in a second state of illumination.

FIG. 4 is a top plan view of the first embodiment of electronic vaping device with response draw lighting, depicted in a third state of illumination.

FIG. 5 is a top plan view of the first embodiment of electronic vaping device with response draw lighting, depicted in a fourth state of illumination.

FIG. 6 is a top plan view of the first embodiment of electronic vaping device with response draw lighting, depicted in a fifth state of illumination.

FIG. 7 is a top plan view of the first embodiment of electronic vaping device with response draw lighting, depicted in a fully-illuminated state.

FIG. 8 is a top plan view of a second embodiment of electronic vaping device with response draw lighting, including a circular-patterned, translucent, illuminable portion, depicted in an unilluminated state.

FIG. 9 is a top plan view of the second embodiment of electronic vaping device with response draw lighting, depicted in a first state of illumination.

FIG. 10 is a top plan view of the second embodiment of electronic vaping device with response draw lighting, depicted in a second state of illumination.

FIG. 11 is a top plan view of the second embodiment of electronic vaping device with response draw lighting, depicted in a third state of illumination.

FIG. 12 is a top plan view of the second embodiment of electronic vaping device with response draw lighting, depicted in a fourth state of illumination.

FIG. 13 is a top plan view of the second embodiment of electronic vaping device with response draw lighting, depicted in a fifth state of illumination.

(Continued)

FIG. 14 is a top plan view of the second embodiment of electronic vaping device with response draw lighting, depicted in a fully-illuminated state.

FIG. 15 is a top plan view of a third embodiment of electronic vaping device with response draw lighting, including a rectangle-patterned, translucent, illuminable portion, depicted in an unilluminated state.

FIG. 16 is a top plan view of the third embodiment of electronic vaping device with response draw lighting, depicted in a first state of illumination.

FIG. 17 is a top plan view of the third embodiment of electronic vaping device with response draw lighting, depicted in a second state of illumination.

FIG. 18 is a top plan view of the third embodiment of electronic vaping device with response draw lighting, depicted in a third state of illumination.

FIG. 19 is a top plan view of the third embodiment of electronic vaping device with response draw lighting, depicted in a fourth state of illumination.

FIG. 20 is a top plan view of the third embodiment of electronic vaping device with response draw lighting, depicted in a fifth state of illumination.

FIG. 21 is a top plan view of the third embodiment of electronic vaping device with response draw lighting, depicted in a fully-illuminated state.

FIG. 22 is a top plan view of a fourth embodiment of electronic vaping device with response draw lighting, including a diamond-patterned, translucent, illuminable portion, depicted in an unilluminated state.

FIG. 23 is a top plan view of the fourth embodiment of electronic vaping device with response draw lighting, depicted in a first state of illumination.

FIG. 24 is a top plan view of the fourth embodiment of electronic vaping device with response draw lighting, depicted in a second state of illumination.

FIG. 25 is a top plan view of the fourth embodiment of electronic vaping device with response draw lighting, depicted in a third state of illumination.

FIG. 26 is a top plan view of the fourth embodiment of electronic vaping device with response draw lighting, depicted in a fourth state of illumination.

FIG. 27 is a top plan view of the fourth embodiment of electronic vaping device with response draw lighting, depicted in a fifth state of illumination.

FIG. 28 is a top plan view of the fourth embodiment of electronic vaping device with response draw lighting, depicted in a fully-illuminated state.

FIG. 29 is a top plan view of a fifth embodiment of electronic vaping device with response draw lighting, including a pentagon-patterned, translucent, illuminable portion, depicted in an unilluminated state.

FIG. 30 is a top plan view of the fifth embodiment of electronic vaping device with response draw lighting, depicted in a first state of illumination.

FIG. 31 is a top plan view of the fifth embodiment of electronic vaping device with response draw lighting, depicted in a second state of illumination.

FIG. 32 is a top plan view of the fifth embodiment of electronic vaping device with response draw lighting, depicted in a third state of illumination.

FIG. 33 is a top plan view of the fifth embodiment of electronic vaping device with response draw lighting, depicted in a fourth state of illumination.

FIG. 34 is a top plan view of the fifth embodiment of electronic vaping device with response draw lighting, depicted in a fifth state of illumination; and, FIG. 35 is a top plan view of the fifth embodiment of electronic vaping device with response draw lighting, depicted in a fully-illuminated state.

The broken lines in the drawings depict environmental subject matter only and form no part of the claimed design. The claim is limited to the geometric elements shown in solid line, and not to the surrounding body of the vaping device.

In each embodiment, the appearance of the response draw lighting for an electronic vaping device transitions between the various depicted states of illumination (see, for example, FIGS. 1-7, FIGS. 8-14, FIGS. 15-21, FIGS. 22-28, and FIGS. 29-35, respectively).

The claimed elements shown in white illustrate unilluminated portions and claimed elements shown in full black illustrate illuminated portions.

1 Claim, 20 Drawing Sheets
